Attorney

UNITED STATES PATENT OFFICE.

ERNEST L. HADDOCK, OF VANCOUVER, BRITISH COLUMBIA, CANADA.

MAGNETO PLUG.

Application filed September 13, 1923. Serial No. 662,517.

To all whom it may concern:

Be it known that I, ERNEST L. HADDOCK, a subject of the King of Great Britain, residing at Vancouver, in the Province of 5 British Columbia and Dominion of Canada, have invented certain new and useful Improvements in a Magneto Plug, of which the following is a specification.

This invention appertains to a terminal 10 plug for magnetos.

In a well known type of automobile, the terminal plug of the magneto becomes quickly fouled and short circuited and thus renders the complete ignition system out of 15 working order. Further the plug is so situated and so arranged in the magneto housing, that the same is not easily removed, and when the same is repeatedly removed the connection between the plug and the 20 magneto housing becomes worn and leaky.

It is therefore a prime object of this invention to provide an improved magneto terminal plug, which is so constructed, that the same will not be easily fouled or short 25 circuited and which is so associated with the magneto casing, that the plug can be quickly removed when necessary without injuring the connection between the plug and the housing.

30 A still further object of the invention is to provide an improved magneto terminal plug of the above character, which will be durable and efficient in use, one that will be simple and easy to manufacture and one 35 which can be placed upon the market at a small cost.

With these and other objects in view, the invention consists in the novel construction, arrangement and formation of parts, as 40 will be hereinafter more specifically described, claimed and illustrated in the accompanying drawings, in which drawings:

Figure 1 is a side elevation of the improved magneto contact or terminal plug.

45 Figure 2 is a vertical longitudinal section through the same.

Figure 3 is a horizontal section through the plug taken on the line 3-3 of Figure 2.

Figure 4 is a horizontal section taken 50 through the plug, on the line 4-4 of Figure 2.

Referring to the drawings in detail, wherein similar reference characters designate corresponding parts throughout the 55 several views, the letter A generally indicates the improved terminal plug, which

comprises a jacket 5, preferably formed of steel, iron or the like. This jacket 5 is reduced at its lower end and provided with external screw threads 6 for permitting the 60 same to be threaded into a screw threaded opening 7 formed in an attaching plate 8. This attaching plate 8 is adapted to be connected to the magneto casing of the automobile with which the plug is associated by 65 suitable screws or the like 9 and if so desired a gasket can be placed between the plate 8 and the magneto casing (not shown), so as to make a tight fit therewith. The upper end of the jacket 5 has its outer surface 70 formed of a polygonal configuration, so as to permit the ready engaging thereof by a wrench or the like. At a point intermediate its ends the jacket 5 is provided with an internal shoulder 10, for a purpose, which 75 will be hereinafter more fully described. As clearly shown in Figure 2 of the drawing the jacket 5 is adapted to receive the porcelain or other insulation body 11 and the same is enlarged at a point intermediate 80 its ends to provide upper and lower shoulders, and it can be seen that the lower shoulder formed by the enlargement 12 rests upon the shoulder 10 formed in the jacket 5. The porcelain body 11 is held in 85 place in the jacket 5 by means of a suitable nut or the like 13. This nut 13 engages the upper shoulder formed by the enlargement 12 on the porcelain and if so desired suitable gaskets can be placed on the upper and 90 lower shoulders defined by the enlargement, so as to prevent injury to the porcelain incident to screwing of the nut 13 into place. A contact rod 15 extends axially through 95 the porcelain body 11 and terminates below the jacket 5 and the porcelain body 11, as is clearly shown in Figure 2 of the drawings. The upper end of the contact rod 15 terminates in a binding post 16 and a suitable binding nut 17 can be provided for holding 100 the magneto terminal wire in place. As clearly shown in Figure 2 of the drawings the upper end of the contact post or rod 15 is limited in its downward movement by suitable nuts and washers 18 which are 105 threaded on the post in contact with the porcelain body 11. The magneto terminal wire is clamped between the nuts 17 and 18 and these nuts can be adjusted so as to regulate the position of the contact rod 15 in the 110 porcelain body 11. The lower surface of the porcelain body 11 is provided with an

enlarged chamber 19 for the reception of an expansion spring 20, which is coiled about the contact rod 15. The upper end of this spring 20 engages the upper end of the chamber, while the lower end of the spring engages a collar 21 formed on the contact rod. This spring serves as means for normally holding the contact post down in the plug and the downward movement is limited by the nuts 18, as heretobefore stated. The extreme lower end of the rod 15 is provided with a substantial conical-shaped contact point 22.

A sliding porcelain protector body 23 receives the lower end of the contact rod 15 and this body 23 is of a sleeve like configuration and has the upper end of the bore thereof enlarged in diameter so as to permit the same to be snugly fitted between the jacket 5 and the lower end of the porcelain body 11. As shown an expansion spring 24 is coiled about the lower end of the porcelain body 11 and engages a shoulder formed in the jacket 5 at one end and the upper end of a porcelain protector sleeve 23 at its lower end. This spring serves as means for normally holding the porcelain body at the lower end of the contact plug and it can be seen that the lower end of the protector porcelain body is flared as at 25 for receiving the contact point 22.

It is obvious that the protector insulating sleeve 23 will effectively prevent the adhering of foreign objects to the contact point 22 and thus prevent short circuiting of the plug. It is also obvious that when it is desired to remove the plug for the replacement of broken parts or for the cleaning thereof, the same can be readily and quickly unthreaded from the attaching plate, without disturbing any other parts of the magneto casing or the like.

Changes in details may be made without departing from the spirit or the scope of this invention.

What I claim as new is:

A terminal plug for magnetos comprising a metal jacket having an annular enlargement therein defining an upper and a lower stop shoulder, a porcelain body fitted in the jacket resting on the shoulder, the lower end of the porcelain body being reduced and extended below the annular enlargement in spaced relation to the inner face of the jacket defining an annular chamber therewith, a nut for holding the porcelain body in position in the jacket on said shoulder, an axially disposed contact rod extending through the porcelain body and terminating below the lower end thereof, a binding post on the upper end of the rod, a contact point on the lower end of the rod, means carried by the upper end of the rod for holding the same in position on the porcelain body and for limiting the sliding movement thereof, a stop collar on said rod, an expansion spring coiled about the rod engaging the collar at its lower end and the porcelain body at its upper end, a porcelain sleeve having a reduced extension slidably disposed in the chamber defined by the jacket and the reduced portion of the porcelain body the reduced portion of the sleeve defining a stop shoulder, the sleeve receiving the lower end of the contact rod and an expansion spring disposed in the chamber having its opposite ends engaging the upper edge of the sleeve and the stop shoulder defined by the annular enlargement of the jacket.

In testimony whereof I affix my signature.

ERNEST L. HADDOCK.
